UNITED STATES PATENT OFFICE.

FREDERICK WETZEL, OF NEW YORK, N. Y., ASSIGNOR OF FORTY ONE-HUNDREDTHS TO
JULIUS K. M. WAIBEL, OF NEW YORK, N. Y.

TRAIN CONTROL.

1,133,900.

Specification of Letters Patent.

Patented Mar. 30, 1915.

Application filed February 27, 1914. Serial No. 821,497.

To all whom it may concern:

Be it known that I, FREDERICK WETZEL, a subject of the Emperor of Germany, residing at New York city, in the county of New

5 York and State of New York, have invented new and useful Improvements in Train Controls, of which the following is a specification.

10 The general objects of this invention are to effect communication between a railroad signal-tower operator and the driver of a locomotive, and to enable the driver to receive the transmitted signals within the confines of his cab.

15 A further object is to effect the retarding of the progress of the locomotive by the signal; and a still further object is to effect the stopping of the locomotive when the semaphore is set for a corresponding reading. And to these ends the invention consists of a trip member positioned in the road-bed between the rails, means located in a signal-tower for actuating the said trip member and means carried by the locomotive 20 and adapted to be operated by the said trip member for controlling the progress of the train.

Other objects will appear and be better understood from that embodiment of my invention of which the following is a specification, reference being had to the accompanying drawings forming part hereof, in which:

30 Figure 1 is an explanatory view showing the coöperating members of the invention. Fig. 2 is a plan view of Fig. 1. Fig. 3 is a detail perspective view of the speed controlling members carried by the locomotive. Fig. 4 is a detail side elevational view of the 35 actuating arms for coöperating with the members on the locomotive. Fig. 5 is a side elevational view of the member located within the signal tower. Fig. 6 is a plan view of a portable arm for operating one of the elements carried by the locomotive for stopping the train.

As shown in the drawings *a* indicates the trip member which is preferably positioned in the road-bed between the rails and in suitable spaced relation to a signal tower *b* in which is located a member *c* for actuating the trip *a* by the connection *d*. The trip *a* is so positioned in the road that it will contact with the members *e* and *f*, carried by the locomotive for retarding and stopping

the train, respectively, and also contact with the member *h* for operating an audible signal *k* preferably located in the cab of the locomotive.

The trip member *a* is formed of a shaft 5 60 which is rotatably positioned in the road-bed between the rails and is provided at one end with the large sheave 6 over which passes the connection *d* after being first trained over the smaller idler sheaves 7—7, as shown 65 in Fig. 1.

Mounted rigidly on the shaft and in suitable spaced relation with each other are a series of radially positioned arms 8, which are adapted to project above the surfaces of 70 the rails and have journaled in their ends the rollers 10. It is obvious that by the action of the connection *d* here shown in the form of the cable 11, any one of the arms may be disposed perpendicularly to the surface of the road-bed, as desired.

The member *c* for operating the trip member is preferably located in the signal-tower and is adapted to be actuated by the towerman, or if desired, this member *c* may be included in the semaphore system. The member *c* consists of a large sheave 12 mounted on one end of the shaft 12', which shaft is journaled on the supports 13 and is adapted to be rotated by the lever 14. This lever has 80 the usual spring-pressed finger 15 which engages in the notches 16 located in the periphery of the sheave 12, as shown. A segmental end-plate 13' is carried by the support 13 and is provided with a centrally located opening 17, for the purpose of viewing the legends 18 marked on the side of the sheave as shown in Fig. 5. It will be noted here that these legends are adapted to show through the opening 17, and thus record the 85 position of the trip-member *a*; however, it is to be understood that this form of recording means is shown for the purposes of illustration, and manifestly any other recording means may be used equally well. The cables 90 11 after passing the idlers 7 adjacent to the trip-member continue to the idlers 19—19 adjacent to the tower *b*, and then pass over the large sheave 12 as shown in Figs. 1 and 5; thus by actuating the member *c*, a corresponding movement is effected by the trip-member *a* and the action is recorded as above 95 described.

As shown in Fig. 1, the members *e*, *f* and *h*, are carried by the locomotive *m*, so that 110

the shoes 20 will depend therefrom and be in a horizontal plane with the end of the arms 8 when the arms are in the perpendicular position. The shoes are located in 5 a bifurcated pocket 21 mounted on the under part of the locomotive and are pivoted therein at one end, as indicated by 22. It will be noted by referring to Fig. 2, that each arm 8 has its respective shoe 22 adapted 10 to contact therewith, and for this reason the shoes are arranged in longitudinal alignment with the arms. Pivotedly carried by each shoe 22 at the free end thereof, is a vertical rod 23 which is adapted to perform its 15 respective function when actuated by the shoe, as will be presently explained.

When it is desired to stop the train by an operator in the signal tower *b*, the member *c* is rotated by the lever 14 until the letter 20 "S" appears on record, as shown. This action sets vertically the arm 8 alining with the member *f*, and it will be noted that as the train passes over this arm, the free end 25 of the shoe will be substantially cammed up by the roller 10 on the arm, thus raising the rod 22 and opening the exhaust-valve 24 of the air-brake system, which is connected thereto. When it is desired to only retard the speed of the train, the member *c* is rotated so as to show the legend "R" whereupon 30 the middle arm 8 will be positioned vertically and the member *c* will be actuated, thus closing the steam-supply valve 25 which is connected to this member as shown. When a clear track is signaled the tower mechanism is actuated which records the legend "C" and the third arm 8 is raised vertically, thus actuating the shoe in member *h*; the rod 23 carried by this shoe 35 is adapted to close the circuit of an electric-signal, which rings and announces to the engine-driver of a clear track. It will be noted here that the pocket 21, which harbors the shoe 22, is substantially cam-shaped 40 and as the train passes over the arms 8, the pocket tends to cam the set arm back to its inoperative position after the shoe 22 is actuated thereby. It will also be noted that the "step" arm is provided at its opposite 45 end with a weight 26, which adapts the arm to be normally set as shown in Figs. 1 and 4; thus, should no signal be given to the train, the same will stop automatically as 50

previously described. A safety lock 27 is shown in Figs. 1 and 4 and consists of an 55 arm 28, which is provided with offset ends 29 and 30, and is pivotally mounted so that one end 30 will rest on the cable 11 and the other end 29 will be disposed in relation to a notch 31 in the sheave 6. It will therefore be seen that should any fracture occur in the cable, and the same become broken, the end 30 will drop, thus causing the end 29 to be directed into the notch 31, and secure the sheave against movement and with 60 the arm for stopping the train in its raised or operative position.

The portable trip-arm shown in Fig. 6, consists of a rigid arm 32 provided with a 70 roller 33, at its end and carried by a support 34 which is adapted to straddle a pair of cross-ties and be detachably secured thereto by the bolts 35 as shown. It is obvious that this trip-member can be placed at any desired location on the track and 75 therefore it is especially adapted to function as a signal or even to stop the train in the case of a wash-out, wreck or the like.

If desired a suitable recording mechanism may be connected to the device in any well-known manner, whereby to keep a monthly record of the various movements of the device.

It is obvious that those skilled in the art may vary the details of construction and 85 arrangements of parts without departing from the spirit of my invention and therefore I do not wish to be limited to such features except as may be required by the 90 claim.

What is claimed as new is:

In a train control, the combination of 95 a trip-member provided with a series of radial arms adapted to be positioned in the path of the train, means for actuating the said arms, a flexible element connecting the actuating means and the trip-member, and a series of members carried by the locomotive and adapted to be operated by the said arms for the purposes set forth.

In testimony whereof I affix my signature in presence of two witnesses.

FREDERICK WETZEL.
